(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design; and,

FIG. 2 is a front view of a second embodiment thereof. The outermost dash-dot broken line in the figures shows a display screen or portion thereof and forms no part of the

(Continued)

claimed design. The innermost dash-dot broken line illustrates portions of the graphical user interface that forms no part of the claimed design.
